United States Patent Office

Des. 186,458
Patented Oct. 27, 1959

186,458

CLOCK OR SIMILAR ARTICLE

William V. Judson, Dover, Mass., assignor to General
Electric Company, a corporation of New York

Application August 27, 1958, Serial No. 52,399

Term of patent 3½ years

(Cl. D42—7)

FIG. 1.

Fig. 1 is a front elevational view of a clock embodying my new design;

Fig. 2 is a side elevational view thereof; and
Fig. 3 is a top plan view thereof.

I claim:

The ornamental design for a clock or similar article, substantially as shown.
